Primary Examiner — Paula Greene(74) *Attorney, Agent, or Firm* — Morgan, Lewis & Bockius LLP(57) **CLAIM**

An ornamental design for the battery, as shown and described.

DESCRIPTION

FIG. 1 is a first perspective view of our new design of our new battery;

FIG. 2 is a second perspective view of the design of FIG. 1;

FIG. 3 is a front view of the design of FIG. 1;

FIG. 4 is a top view of the design of FIG. 1;

FIG. 5 is a bottom view of the design of FIG. 1;

FIG. 6 is a left hand side view of the design of FIG. 1; and,

FIG. 7 is a right hand side view of the design of Figure.

The broken lines in the above described FIGS. 1-7 are for illustrative purposes only and form no part of the claimed design.
